UNITED STATES PATENT OFFICE.

GEORGE SEILER AND FRANKLIN EMIG, OF SPRING FORGE, PENNSYLVANIA,
ASSIGNORS OF ONE-THIRD TO GEORGE G. WAGNER, OF SAME PLACE.

MACHINE FOR SEPARATING PULP FROM LIQUIDS.

SPECIFICATION forming part of Letters Patent No. 514,780, dated February 13, 1894.

Application filed April 10, 1893. Serial No. 469,764. (No model.)

To all whom it may concern:

Be it known that we, GEORGE SEILER and FRANKLIN EMIG, citizens of the United States, residing at Spring Forge, in the county of York 5 and State of Pennsylvania, have invented certain new and useful Improvements in Machines for Separating Pulp from Liquids; and we do hereby declare the following to be a full, clear, and exact description of the invention, 10 such as will enable others skilled in the art to which it appertains to make and use the same.

Our invention relates to a machine for recovering wood pulp from caustic liquors without the use of an undue or large quantity of 15 water for washing the pulp, and the machine may also be advantageously used for the recovery of bark from the coloring matter or liquid used in bark mills.

The objects of our invention are to provide 20 simple and efficient means whereby the caustic liquor is extracted or pressed from the wood pulp and the liquor allowed to run off into one tank or compartment while the pulp is discharged from the pressure mechanism into 25 another compartment, such operations and separation being effected mechanically and expeditiously with the use of a very small proportion of water, or by omitting the supply of water altogether, thus effecting a saving not 30 only in the quantity of the pulp recovered from the caustic liquor but also accomplish the end in a much shorter space of time and at a greatly reduced cost.

With these ends in view, our invention consists in the combination with a suitable frame, 35 a supply hopper therein, a set of co-acting pressure rolls supported in the frame below the supply hopper, a traveling carrier arranged to travel between the upper and lower 40 rolls of said coacting pressure rolls, a tank for receiving the liquid situated beneath one part of the carrier, and a water supply tank at or near the discharge end of the traveling carrier for the purpose of supplying water to 45 the compressed pulp after it has passed between the pressure rolls and the liquor extracted therefrom, all as will be hereinafter more fully described.

The invention further consists in the novel 50 combinations of devices and peculiar construction and arrangement of parts as will

be hereinafter more fully described and particularly pointed out in the claims.

We have illustrated the preferred embodiment of our invention in the accompanying 55 drawings, forming a part of this specification, and in which—

Figure 1 is a side elevation, and Fig. 2 is a longitudinal central sectional view of our machine. Fig. 3 is an enlarged side view of the 60 upper part of the frame showing the removable bearing rails in which the supply hopper, the upper rolls of the coacting pressure rolls, and water tank and scraper knife are supported, to permit ready and convenient 65 access to any part of the machine.

Like letters of reference denote corresponding parts in all the figures of the drawings, referring to which—

A designates the main or supporting frame 70 of the machine, which frame may be of any suitable or preferred construction adapted for the purpose of sustaining all the operative parts or mechanisms for compressing and extracting pulp or bark from the liquors present 75 therein. At the top side of this frame A, and preferably near one end thereof, we provide a supply hopper B into which the pulp or bark is deposited by any suitable conveyer or in any other manner. We preferably support 80 this hopper on the frame in a manner to permit of the ready removal of the hopper, as will presently appear.

C is a traveling conveyer or apron which is 85 arranged within the sides and ends of the frame A, said apron or conveyer being situated in a horizontal position on a plane beneath the hopper B so as to receive the pulp or bark from said hopper. We preferably make this traveling apron or conveyer of wire 90 or reticulated, foraminous material, although any other material suitable for the purpose of permitting the liquor or liquid matter to pass through the conveyer or apron after it has been extracted or pressed from the pulp 95 or bark, may be used.

D, D', are the set of coacting pressure rollers, D being the upper roller or rollers, and D' being the lower roller or rollers, of the set of coacting pressure rollers. This set of co-acting rollers may consist of only two rollers (an upper and lower roller); but we prefer to 100

employ a series of four rollers, two being arranged above and the other two below the apron. This conveyer or apron C is arranged to travel or pass between the upper and lower 5 rollers of the set of coacting pressure rollers, whereby the apron is made to convey the pulp or bark from the hopper between the upper and lower rollers and thus the pulp or bark is subjected to pressure between the upper 10 and lower rollers to force out the liquid present or contained in the pulp.

The set of pressure rollers are situated at one side of the supply hopper, and at the other side of said pressure rollers from the 15 supply hopper is arranged a tank E, which is provided, on the side adjacent to the pressure rollers, or in its bottom, with a discharge opening e. This tank E is to be supplied with water, in order to be discharged into the 20 pulp or bark after it has been pressed by the rollers, so that the pulp or bark will contain sufficient water, or be in a semi-fluid state, for the purpose of conveniently pumping the pulp or bark back to the mill by any suitable 25 form of pumping mechanism (not shown).

In the lower part of the frame, below the traveling conveyer or apron, and in vertical line with the supply hopper is a tank F in which the caustic liquid or other liquid matter 30 extracted from the wood pulp or bark, is adapted to flow when it is pressed or extracted from the pulp or bark, and this receiving tank F has a vertical wall f at its inner end, which wall serves to isolate the receiving 35 tank F from the discharge chute G which is inclined downward from the wall f of said receiving tank and arranged below the discharge end of the conveyer or apron C to receive the pulp or bark from the latter after 40 it has been pressed by and between the coacting pressure rolls.

The conveyer or apron C is of the endless variety, and it is supported at its ends by the power-driven and idler rollers H, H', around 45 which the endless conveyer or apron passes, and the shafts of these rollers H, H' are suitably journaled in bearings supported on the sides of the frame A, as shown, the shaft of the power-driven roller H being provided 50 with a pulley h around which passes a belt for communicating power to the roller H and thus to the apron.

On the sides of the frame A are fitted the removable bearing rails I, I, of the machine, 55 which bearing rails are notched or provided with caps which fit over the shafts of the driving and idler rollers H, H', and the shafts or trunnions of the lower rolls D', D' of the set of coacting pressure rollers. The bearing 60 rails are fitted between the end pieces of the frame A, to which they are connected by slides or ways to prevent lateral or sidewise displacement of said bearing rails, and they are prevented from vertical movement and held 65 down in position by any suitable fastenings. These bearing rails are further provided with the boxes or journal bearings for the shafts

or trunnions of the upper rolls D, D, of the set of coacting pressure rolls, over which shafts or trunnions are fitted the caps i, i, 70 that hold the rolls D, D, in place and which permit of the ready removal of the rails from their bearings in the rails I, I.

The supply hopper B of the machine is fitted in place between the inclined ways j, j, shown 75 by full lines in Fig. 2 and by dotted lines in Fig. 1, said ways j being on the inner sides of the rails I, I, so that the hopper can be readily lifted out of position between the rails I, I. Said hopper is further provided, in its bottom, or on the side adjacent to the roll D, with an outlet opening b, the area or size of which can be regulated by means of the gate-valve K which is fitted to slide between the ways or strips k, k, attached to one side of the hopper. 85

The supply tank, for the water, E, is held in place by means of the lugs or flanges l, l, provided at the ends thereof, which lugs are fitted in place in the openings formed in the retainers L, L, fixed to the upper side of the 90 bearing rails I, I, suitable keys or wedges l', l', being inserted between the retainers L and the lugs l on the supply tank to hold the latter firmly, but detachably, in position.

In order to keep the upper roll D of the set of 95 pressure rollers clear, and prevent wood pulp or bark from adhering to the surface of said roll, we provide the supply-tank E with a scraper or knife M which projects from the lower part of the hopper until it terminates 100 very close to the surface of the roll D.

The rolls D, D, D', D', constituting the set of pressure rolls are geared together so that they all rotate or turn in one direction, to effect the compression of the pulp or bark, 105 and thus extract the liquid matter therefrom; but in the drawings we have not deemed it necessary to illustrate fully this gearing as the same will be readily understood and supplied by a mechanic skilled in the art. 110

This being the construction of our machine, the operation thereof may be described as follows: Power is communicated by a belt to the driving pulley of the shaft-roller H to move the endless conveyer or apron, and the pressure rolls are also set in motion in any convenient way. The pulp and its caustic liquor, or the bark and coloring matter, are supplied to the hopper B in any appropriate way while water is supplied to the tank E. To feed the 120 pulp or bark and their contained liquid matter to the machine, the gate-valve of the supply hopper B is opened, and the pulp or bark with their liquid is allowed to pass through the opening b, in regulated quantities, and 125 thus deposited upon the foraminous or other form of conveyer or apron C. This conveyer transfers to the pressure rolls the pulp or bark, and as the matter is carried through the machine by the apron or conveyer, the 130 liquid matter in the pulp or bark is extracted or pressed therefrom. The liquid flows readily through or from the apron into the tank at the bottom of the machine, while the solid

particles of wood pulp or bark are carried over the discharge end of the apron and deposited on the inclined discharge-chute, so that the pulp or bark and liquid are mechanically separated and discharged separately from the machine.

We have found that it will not be necessary to use any, or at most very little, water to effect the separation of the liquid matter from the solid matter of the wood pulp or bark; but to enable the pulp or bark to be conveniently pumped back to the mill, we prefer to use a small quantity of water to be supplied to the solid particles of pulp or bark as it passes between or from the pressure rolls onto the inclined discharge chute. The water thus supplied by the tank E to the pulp or tan bark after the liquid has been extracted therefrom serves to reduce the bark or pulp to a semi-fluid condition for its convenient transportation, by pumping, back to the mill.

We are aware that changes in the form and proportion of parts and details of construction of the mechanism herein shown and described as an embodiment of our invention can be made without departing from the spirit or sacrificing the advantages thereof, and we therefore reserve the right to make such modifications or alterations as fairly fall within the scope of the invention.

In order to provide a proper support for the apron or conveyer, and to prevent the same from sagging, we may provide a series of two or more small sustaining rollers N which are placed at one side of the set of coacting pressure rolls and are loosely journaled in bearings on the sides of the frame A of the machine.

Having thus fully described our invention, what we claim as new, and desire to secure by Letters Patent, is—

1. In a machine for the purposes described, the combination with a suitable frame, and a supply hopper, of a set of coacting pressure rolls, a conveyer arranged to travel between said pressure rolls and carry the solid matter from the hopper to and through said pressure rolls, a liquid-receiving tank below one part of the conveyer, and a water-supply tank arranged over the delivery part of the conveyer, at one side of the pressure-rolls, to supply water to the solid matter after it has passed between the rolls and the liquor expelled therefrom, substantially as and for the purposes described.

2. In a machine for the purposes described, the combination with a suitable frame, of a supply hopper, a set of coacting pressure rolls, a conveyer arranged below said hopper and between said rolls, and a liquid supply tank arranged relatively to said apron and the pressure-rolls to supply a limited quantity of water to the pulp or bark after its com-

pression between said pressure-rolls, substantially as and for the purpose described.

3. In a machine for the purposes described, the combination with a suitable frame, and a supply hopper, of a set of coacting pressure-rolls, a conveyer arranged to travel between said pressure-rolls, the receiving tank below one part of the apron, a discharge chute below the other end of the apron, a liquid supply-tank arranged to deliver liquid to the pulp or bark after its compression between said pressure-rolls, and a scraper or knife supported in position to clear the upper pressure-roll from pulp or bark that adheres thereto, substantially as and for the purpose described.

4. In a machine for the purposes described, the combination of an endless apron supported by the driving and idler rollers, the set of coacting pressure-rolls constructed for positive rotation in one direction and arranged to bear against the lower and upper sides of said apron, the supply hopper situated above the apron at one side of the pressure-rolls, a supply tank likewise situated above the apron and on the opposite side from the pressure-rolls, and the receiving and discharge means for the pulp or bark and liquid below the apron, substantially as and for the purposes described.

5. In a machine for the purposes described, the combination of a frame provided with removable bearing rails, the endless apron having its driving and idler rollers journaled in the sides of the frame, the set of coacting pressure rolls having the lower rolls journaled in the sides of the frame and its upper rolls journaled in the removable side rails, a supply hopper carried by said removable side rails, a supply tank also carried by said bearing rails, and the receiving tank and discharge chute fixed to the sides of the frame below the apron, substantially as and for the purpose described.

6. In a machine for the purposes described, the combination of a main frame provided with the removable bearing rails, an endless apron having its driving and idler rollers journaled in the sides of the main frame, the coacting pressure rolls having its upper rolls journaled in the bearing rails and its lower rolls journaled in the sides of the frame, a supply hopper removably supported between said bearing-rails, a supply tank detachably fastened to the bearing rails, and the receiving tank and chute fixed to the frame below the apron and at opposite ends thereof, substantially as and for the purpose described.

In testimony whereof we affix our signatures in presence of two witnesses.

GEORGE SEILER.
FRANKLIN EMIG.
